UNITED STATES PATENT OFFICE.

ALFRED WEILAND, OF EAST ORANGE, NEW JERSEY.

CARBURETER FOR INTERNAL-COMBUSTION ENGINES.

1,274,965.

Specification of Letters Patent. Patented Aug. 6, 1918.

Application filed February 17, 1917. Serial No. 149,186.

To all whom it may concern:

Be it known that I, ALFRED WEILAND, a citizen of the United States, residing at East Orange, county of Essex, and State of New Jersey, have invented a certain new and useful Improvement in Carbureters for Internal-Combustion Engines, of which the following is a specification.

The present invention relates, generally, to the supply of liquid fuel and air to the motor intake or pipe leading to the cylinder or cylinders of an explosive engine and relates more specifically to the regulation and control of the mixture in accordance with load conditions or the demands of the motor.

It is an object of the invention to provide means which are automatically responsive to pressure conditions imposed by the motor during its operation and whereby such means not only regulate the explosive mixture as to quantity delivered from the carbureter, but furthermore, definitely proportion the content of the mixture, that is to say, under certain load conditions, the liquid fuel content of the mixture may be increased as required to meet that condition, while at another time, the air content may be increased to meet another existing condition.

It is a further object of the invention to provide a complete unitary carbureting and fuel feeding device wherein a main fuel feeding reservoir is employed for supplying liquid fuel to the main jet or nozzle of the carbureter and in addition an auxiliary reservoir is provided within the same carbureter casing and serves to automatically replenish at intervals the supply in the main reservoir and furthermore the said auxiliary reservoir acts automatically to refill itself from a low level liquid fuel supply.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings:

Figure 1 represents a sectional elevation of a carbureter embodying my invention. 55

Fig. 2 represents a plan of the same.

Fig. 3 represents a section on line 3—3 of Fig. 1.

Fig. 4 represents a section on line 4—4 of Fig. 1.

1 designates the main casing of the carbureter which is substantially centrally apertured to form the carbureting chamber 2 and is additionally cored out to form the annular main fuel reservoir 3 the storing reservoir 4 and the auxiliary reservoir 5. In the present instance, the casing 1 is provided with a plurality of depending webs 6 preferably three in number and connected for a portion of their length with an annular body 7, the upper part of which is suitably spaced from the bottom portion of the casing proper to provide air passages 8 which form the main air supply to the carbureting conduit 2. 65

9 designates a tubular nozzle suitably secured to the casing 1 and extending axially into the carbureting chamber 2 and having its bore 10 in open communication with the said chamber 2 while its opposite end is in communication with a conduit 11 having free unobstructed communication with the main fuel reservoir 3. The bore 10 also communicates with suitable ports 12 which are in communication with an air inlet pipe 13 which permits a small primary supply of air to mix with the liquid fuel within the nozzle 9. A pressure regulated valve 14 extends through the bore 10 and is employed to control the liquid fuel from the passage 11 as conditions warrant and this valve is under the direct control of certain devices hereinafter to be described. Referring now to the auxiliary chamber 5, it will be noted that it receives liquid fuel by way of the inlet passage 15 which has communication with a suitable source of supply, such as a low level tank or otherwise and which passage 15 is controlled by a valve 16 located 100 in the path of movement of the float 17. This float is suitably pivoted at 18 for swinging movement under change of level conditions and has an extension arm 19 which is connected to a reciprocable valve stem 20 105

which carries the valve 21. The valve 21 is arranged and serves to control the outlet 22 from the chamber 5 and it will be evident, from the foregoing construction, that 5 when the valve 21 is closed the valve 16 must be opened, so that in one instance the chamber 5 is filling and in the other it is discharging. Furthermore, the chamber 5 is normally subject to vacuum conditions, 10 since it has communication by way of the ports 23 and 24 with the outlet 25 of the carbureting chamber 2, this outlet, as will be understood, being on the motor side of the throttle 26. The throttle is under control 15 of the throttle lever 27 as usual.

The storing reservoir 4 is formed as an annular chamber between the main reservoir 3 and the auxiliary reservoir 5 and has a downwardly extending flange 28 which 20 forms a discharge passage 29, the mouth of which, under normal conditions of operation, is sealed by the liquid fuel in the main reservoir 3. This latter reservoir is provided with an air vent 30 which allows air 25 to enter the said main reservoir to permit the liquid fuel to flow to the nozzle and to also allow air to find its way through the liquid seal into the storage chamber 4, so that the liquid fuel therein may discharge 30 in required amounts.

Referring now to the automatic regulation and proportioning of the liquid fuel and the air, 31 designates a valve of the sliding sleeve type which is adapted to control the 35 air openings 8 and which is provided with extensions 32 which join a follower valve 33 which is closed at one end by the head 34 and guided by the tubular extension 35 which slides upon the nozzle member 9. It 40 will be understood that the valve extensions 32 are spaced apart, as shown in Fig. 3, so that the air entering by way of the passages 8 and traveling over the body 7 may pass through into the sleeve 31 and thence to the 45 chamber 2. The sleeve valve 31 has a positive connection, such as shown at 36, with the needle valve 14 and consequently any movement of the sleeve valve to regulate the air supply will correspondingly cause 50 a regulation of the main fuel supply. Normally, the valve 31 is held in its open position by the action of the coiled spring 37, the tendency of which is to press the valve upwardly as shown in Fig. 1.

Referring now to the means for moving the valve 31 and its associated parts in the opposite direction, 38 designates a pipe terminating at one end adjacent the inlet end of the carbureting chamber and communicating 60 with the inclosed space formed by the valve 33, by way of the port 39. The opposite end of the pipe 38 communicates with a relatively small chamber 40 which also communicates with the aforesaid ports 23

and 24. A piston 41 is mounted for sliding movement within this chamber 40 and carries a valve 42 for the purpose of controlling the passage 23, though this latter is not intended to be entirely cut off at any time from pressure conditions in the chamber 40 and 70 therefore the valve 42 has a port 43 as a means of communication between the two chambers. A coiled spring 44 serves as a means to normally press the piston 41 in a direction necessary to maintain the valve 42 75 open while a cap 45 seals the end of the chamber 40 and also limits the movement of the piston.

In the operation of the carbureter, the main jet nozzle 9 receives its liquid fuel 80 from the reservoir 3 and also a primary supply of air by way of the tube 13, though the main body of air enters the carbureting chamber 2 by way of the openings 8 between the legs or extensions 32 of the valve 85 31. The main fuel reservoir 3 continues to supply liquid fuel to the nozzle while air in the meantime finds its way around the liquid seal opening of the flange 28 and bubbles into the storage reservoir 4 as the stored 90 liquid fuel gradually feeds into the main reservoir. While this fuel is being used up by the nozzle, the auxiliary reservoir 5 is being replenished through the vacuum built up by the suction from the intake and 95 through the ports 23 and 24. As soon as the liquid in the chamber 5 reaches a definite level, the rise of the float 17 closes the valve 16 and opens the valve 21, and since at this time the liquid in chamber 4 has dropped its 100 level below the outlet 22, there is an outlet then provided for the air trapped in the chamber 4, with the result that the liquid in the auxiliary chamber 5 discharges into the storage reservoir until the float acts to 105 close the valve 29.

Under normal conditions, with the throttle wide open the slide valve 31 is held open by the action of the spring 37 and consequently the full air inlet opening is provided to the mixing chamber. Under other conditions, however, with the main throttle closed or partially closed and under which conditions a quite different mixture is required, there will be a considerably increased 110 vacuum in the small regulating chamber 40 which produces sufficient suction below the valve 33 to overcome the action of the spring 37 so that the valve 31 for the air and the valve 14 for the liquid fuel are both brought 120 to a more nearly closed position, thus cutting down not only the air but the liquid fuel and this cutting down or diminishing of the supply may be definitely proportioned by varying the relative dimensions of the 125 aforesaid valves and parts. It will be understood that the action and operation of controlling the valve 31 from pressure con-

ditions existing in the motor intake is quite distinct and separate from the operation of the dash-pot plunger valve 41 and I have merely illustrated the pipe 38 as connected to the chamber 40 for convenience, since it will be understood that any suitable manner of transmitting the pressure conditions in the motor intake below the valve member 34 may be employed.

10 In connection with the maintenance of a vacuum in the auxiliary chamber 5, it should be noted that the function of the dash-pot valve 41 is to vary the opening or size of the passage leading from the auxiliary chamber 5 to the motor intake and thus regulate the suction in such a manner that the vacuum in the chamber 5 remains substantially constant. Thus, for example, as shown in Fig. 1, where the valve 41 is closed, 15 except for the port 43, it will be evident that conditions of a maximum suction exist in the motor intake and consequently the communicating opening with the chamber 5 is at a minimum, with the result that the 20 vacuum in the chamber 5 remains practically unchanged. Naturally, as the suction in the motor intake becomes less under free running conditions, the valve 41 opens in a proportionate degree and thus varies the opening 25 as required.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of 40 modifications in various particulars without departing from the fair spirit or scope of the invention or sacrificing any of its advantages.

45 What I claim is:

1. In a carbureter, a main fuel reservoir having an air vent above the normal liquid level, a storing reservoir having an outlet below the normal level in said main reservoir forming a liquid seal, an auxiliary reservoir having an outlet to said storing reservoir, a valve for said auxiliary reservoir outlet, a fuel inlet to said auxiliary reservoir, a valve controlling said inlet, a float 50 in said auxiliary reservoir arranged to actuate both of said valves, and a conduit forming a communication between the auxiliary reservoir and a source of suction whereby a condition of vacuum is maintained in said auxiliary reservoir.

2. In a carbureter, a casing forming a carbureting chamber, a main fuel reservoir and an auxiliary supply reservoir, a fuel nozzle arranged to deliver fuel to said carbureting

chamber and having communication with 65 said main reservoir, means controlled by the liquid level in said auxiliary reservoir for alternately connecting said auxiliary reservoir with a source of low level liquid supply and with said main reservoir, and means for automatically maintaining a substantially constant vacuum in said auxiliary reservoir.

3. In a carbureter, a casing forming a carbureting chamber, a main fuel reservoir 75 and, an auxiliary supply reservoir, a fuel nozzle arranged to deliver fuel to said carbureting chamber and having communication with said main reservoir, means controlled by the liquid level in said auxiliary 80 reservoir for alternately connecting said auxiliary reservoir with a source of low level liquid supply and with said main reservoir, and means controlled by pressure conditions in the motor intake for maintaining 85 a substantially constant vacuum in said auxiliary reservoir.

4. In a carbureter, a casing forming a carbureting chamber, a main fuel reservoir and an auxiliary supply reservoir, a fuel 90 nozzle arranged to deliver fuel to said carbureting chamber and having communication with said main reservoir, means controlled by the liquid level in said auxiliary reservoir for alternately connecting said auxiliary reservoir with a source of low level liquid supply and with said main reservoir, a conduit forming a communication 95 between said auxiliary reservoir and the motor intake to establish vacuum conditions in said auxiliary reservoir and means to automatically vary the size of said conduit, whereby the vacuum conditions in said auxiliary reservoir remain substantially constant.

5. In a carbureter, a casing forming a carbureting chamber, a main fuel reservoir and an auxiliary supply reservoir, a fuel nozzle arranged to deliver fuel to said carbureting chamber and having communication with said main reservoir, means controlled by the liquid level in said auxiliary reservoir for alternately connecting said auxiliary reservoir with a source of low level liquid supply and with said main reservoir, a conduit forming a communication between said auxiliary reservoir and the motor intake to establish vacuum conditions in said auxiliary reservoir, a valve for varying the opening of said conduit, said valve having 110 a port therethrough to always maintain communication between said auxiliary reservoir and said motor intake, and means controlled by pressure conditions in said motor intake for varying the position of 115 said valve.

6. In a fuel feeding device for carbureters, an auxiliary receptacle for liquid fuel

- having communication with a low level liquid fuel supply, a reservoir for supplying liquid fuel to a carbureting chamber, means to automatically replenish the fuel reservoir from said auxiliary receptacle, means to normally subject said receptacle to vacuum conditions and means controlled by pressure conditions in the motor intake for maintaining said vacuum in said receptacle substantially constant under all motor running conditions.
7. In a fuel feeding device for carbureters, an auxiliary receptacle for liquid fuel having communication with a low level liquid fuel supply, a reservoir for supplying liquid fuel to a carbureting chamber, means to automatically replenish the fuel reservoir from said auxiliary receptacle, means to normally subject said receptacle to vacuum conditions, and means embodying a valve dash-pot controlled by pressure conditions in the motor intake for maintaining said vacuum in said receptacle substantially constant under all motor operating conditions.
8. In a carbureter, a main fuel reservoir having an air vent, a storing reservoir provided with an outlet communicating with said main reservoir and positioned to be liquid sealed and unsealed by the contents of said main reservoir, an auxiliary reservoir having an outlet to said storing reservoir, and an inlet from a liquid fuel supply, means controlled by level conditions for opening and closing said auxiliary reservoir inlet and outlet and means to automatically replenish said auxiliary reservoir from a low level source.
9. In a carbureter, a main fuel reservoir having an air vent, a storing reservoir provided with an outlet communicating with said main reservoir and positioned to be liquid sealed and unsealed by the contents of said main reservoir, an auxiliary reservoir having an outlet positioned to be liquid sealed and unsealed by the contents of said storing reservoir and means controlled by level conditions for rendering said auxiliary reservoir outlet operative or inoperative to the liquid sealing means according to conditions.
10. In a carbureter, a main fuel reservoir having an air vent, a storing reservoir provided with an outlet communicating with said main reservoir and positioned to be liquid sealed and unsealed by the contents of said main reservoir, an auxiliary reservoir having an outlet positioned to be liquid sealed and unsealed by the contents of said storing reservoir, means controlled by level conditions for rendering said auxiliary reservoir outlet operative or inoperative to the liquid sealing means according to conditions, and means to continuously maintain said auxiliary reservoir in communication with the motor intake.

In testimony whereof, I have hereunto signed my name.

ALFRED WEILAND.
